OTTO A. HOKANSON AND JAMES F. KOCA, OF WOODSTOCK, ILLINOIS, ASSIGNORS TO WOODSTOCK TYPEWRITER COMPANY, OF WOODSTOCK, ILLINOIS, A CORPORATION OF ILLINOIS.

CASE-SHIFT MECHANISM FOR TYPEWRITERS.

Application filed October 5, 1925. Serial No. 60,395.

This invention relates to typewriter mechanism having power actuated apparatus for operating the moving parts.

The object of the invention is to provide mechanism of the class named in which the case shift is effected by means of a power actuated device and in which actuating mechanism of improved construction and operation is employed.

10 The invention is exemplified in the combination and arrangement of parts shown in the accompanying drawings and described in the following specification, and it is more particularly pointed out in the appended 15 claims.

In the drawings—

Fig. 1 is a side elevation of a portion of a typewriter having one embodiment of the present invention applied thereto;

20 Fig. 2 is a fragmentary view looking from the right in Fig. 1;

Fig. 3 is a vertical sectional view taken just inside the side frame of the typewriter;

25 Fig. 4 is a fragmentary elevation showing a modified detail; and

Fig. 5 is a view looking from the right in Fig. 4, with parts omitted.

The numeral 10 in Fig. 1 of the drawings 30 designates a portion of the side frame of a typewriter which supports an electric solenoid 11 having a plunger 12. Current is supplied to the solenoid 11 from any suitable source through conductors 13 and 14.

35 The conductor 14 is connected to a binding post 15 carried by an insulating block 16 adjustably secured to an arm 17 by means of screws 18. The arm 17 is pivotally mounted on the frame of the machine and

40 is provided with an extension 19 having an inclined slot 20. The inclined slot 20 is engaged by a pin 21 carried by a link 22 having sliding connection with a screw 23 on the side of the machine frame. The

45 upper end of the link 22 is pivoted at 24 to a hand lever 25. The hand lever 25 is pivoted at 26 and carries a pin 27 which engages openings 28 in an index plate 29. A spring 30 normally holds the

50 pin 27 in engagement with one of the openings 28. The lever 25 has a finger-piece 31 by means of which it may be drawn outwardly against the tension of the spring 30

to shift the pin 27 from one to another of the holes 28, thus raising or lowering the 55 link 22. This movement of the link 22 will swing the arm 17 forward and rearwardly, shifting the position of the insulator block 16 and the binding post 15. The binding post 15 carries a contact point 32 for engaging a corresponding point 33 on a lever 34. The lever 34 swings about a pivot 35 on the frame of the machine and is connected with a lead 36 which extends through switch mechanism 37 and conductor 38 to the source 60 of power. The lever 34 has a tail-piece 39 which carries a slide 40 normally drawn downwardly by a spring 41. An arm 42 is secured to a rock shaft 43 which extends across the frame of the machine. The arm 70 42 is provided with a lug 44 which engages a projection 45 on the tail-piece 39. The slide 40 is provided with a projection 46 which is normally positioned just above the lug 44. A spring 47 is connected to the rock 75 shaft 43 and to the lever 34 tending to rotate the rock shaft in a clockwise direction and to swing the contact 33 toward the contact 32. The lug 44 engaging the projection 45 holds the contact 33 out of engagement against the tension of the spring 47. A bar 49 is secured to the rock shaft 43 and extends across the frame of the machine in position to be engaged by contact members 50 on the key levers 51, as shown in 80 Fig. 3.

When a key lever is depressed the rock shaft 43 is moved in a counter-clockwise direction raising the lug 44 out of engagement with the projection 45 and permitting the 90 spring 47 to swing the contact 33 against the contact 32 thus closing the circuit through the solenoid 11. This will energize the solenoid and draw the plunger 12 upwardly. The plunger 12 is provided with a pawl 52 95 which engages a ratchet wheel 53 on a shaft 54 extending across the machine. The shaft 54 is provided with teeth 55 which are moved in a counter-clockwise direction each time the ratchet 53 is operated by the solenoid. The type bars 56 are pivoted at 57 in the usual way and provided with sub-levers 58 which carry actuators 59 having teeth 60 in position to engage the teeth 55. When a key lever is depressed the actuator 100 105 59 corresponding to that key lever is moved

downwardly by a contact finger 61 into the path of the teeth 55 so that when the solenoid is energized the actuator is moved forwardly to operate the corresponding type 5 bar 56. At the forward end of the movement of the actuator 59 it is disengaged from the teeth 55 by an adjustable stop 62 which engages a cam surface 63 on the actuator 59. A roller 64 is carried on an arm 65 10 pivoted at 66 on the frame of the machine and engages a star-wheel 67 to prevent overthrow of the ratchet wheel 53 when operated by the solenoid. A second arm 68 is pivotally mounted at 66 on the frame of the machine and is provided with an upward extension 69 having a finger 70 adjustably mounted thereon by screws 71 and 72. When the solenoid is energized the finger 70 is moved to the left, as viewed in Fig. 1, and 15 engages a pin 73, Fig. 2, carried by the tail-piece 39. This swings the tail-piece 39 to the left and moves the contact 33 out of engagement with the contact 32.

The spring 41 is placed under tension by 25 the lug 44 when the arm 42 is moved upwardly by rotation of the rock shaft 43. As soon as the tail-piece 39 is moved to the left the projection 46 will clear the lug 44 and the spring 41 will move the projection 46 30 behind the lug 44 thus locking the tail-piece 39 in position to hold the contact 33 out of engagement with the contact 32. When the key-lever is released the lug 44 will move from the projection 46 onto the projection 35 45 thus retaining the contacts 32 and 33 out of engagement. It will thus be seen that upon depression of a key lever the actuator tooth 60 is moved into the path of one of the teeth 55 after which the circuit is closed by 40 the contact points 32 and 33 and the solenoid 11 energized to impart partial rotation to the shaft 54 thus operating the type bar. Immediately upon operation of the solenoid the contact is automatically broken and 45 locked in open position by the mechanism connected with the plunger 12 which returns the lever 34 to its inactive position.

At each side of the machine there is provided a case shift lever 75 having a projection 50 76 arranged to engage the bar 49 and oscillate the shaft 43 to close the solenoid circuit through the mechanism already described. The case shift lever 75 is provided with a pin 77 which engages a slot 78 on a lever 79 pivotally mounted at 80. The lever 79 carries a downwardly projecting arm 81 having a forwardly bent extension 82. The extension 82 is provided with a pin 83 which underlies a finger-piece 84 secured to a stud 55 shaft 85 journaled in the side of the machine frame. The stud shaft 85 has an arm 86 secured thereto which carries a pin 87 engaging a slot 88 in a plate 89. The plate 89 is 60 65 slidably mounted on a stud 90 projecting from the frame of the machine and also has

sliding connection with a stud 91 on a lever 92, the lever 92 being pivoted on the stud 90. The plate 89 is provided with a nose-piece 93 which normally clears a pin 94 on the plunger 12, but when the stud shaft 85 is 70 oscillated by the extension 82 of the lever 81 the nose-piece 93 will be projected into the path of the pin 94. This occurs on depression of a shift key prior to engagement of the contacts 32 and 33 so that when the 75 solenoid is energized the plate 89 will be swung upwardly about the pivot 90 and the lever 92 will be given a partial rotation in a clockwise direction, as viewed in Fig. 1. The lever 92 has a pivotal sliding engagement at 80 95 with an arm 96 fixed to a shaft 97 which extends across the frame of the machine. The shaft 97 has upwardly projecting arms 98 which are connected by springs 99 with downwardly projecting arms 100 connected 85 with the shift frame 101. The shift frame 101 is pivoted at 102 on the typewriter frame and carries a shift rail 103 on which a roller 104 travels, the roller 104 being arranged to support the platen carriage in the usual manner so that when the shift rail 103 is raised the platen carriage will be shifted. It is thus seen that depression of the shift lever will first position the nose-piece 93 to be actuated by the solenoid after which the shift 95 frame is raised through connecting levers and the spring 99. Immediately after operation of the solenoid it will be de-energized by the mechanism already described. It is, however, desirable to sustain the platen in 100 its upper position until the shift lever is released. This is accomplished by means of an arm 105 secured to the shaft 97 in position to engage a roller 106 carried by a lever 107 pivoted at 108 on the lever 81. A spring 105 109 normally urges the roller 106 rearwardly against a stop 110 on the lever 81. When the shift key is depressed the lever 81 moves rearwardly past the forward end of the arm 105 so that the roller 106 is disposed beneath 110 the cam surface 111 at the end of the arm 105. As soon as the shaft 97 is actuated by the solenoid the arm 105 will be moved downwardly and will pass the roller 106, which is permitted to spring inwardly by the 115 elasticity of the spring 109. The spring 109 immediately moves the roller 106 rearwardly above the end of the arm 105 and against the stop lug 112. This will prevent return rotation of the shaft 97 and hold the platen carriage in its shifted position so long as the shift lever is depressed. When the shift lever is released the stop 110 will draw the lever 107 and the roller 106 forwardly to release the arm 105 and permit the platen to 125 return to its lower position.

The case shift levers and their associated mechanism are arranged one at each side of the machine so that the platen may be shifted by either hand of the operator. The only 130

force necessary is that required to depress the shift lever against the tension of its spring and to move the contact mechanism. The force for lifting the platen is supplied by the solenoid. So long as the shift lever is held down the platen will remain in its upper position, but the force required for holding the key down is very small since the weight of the platen is not sustained by the key, but by the locking mechanism described. The force of impression made by the type bars may be controlled by shifting the finger-piece 31 up or down. This moves the contact piece 32 so as to vary the period of contact and thus regulate the force of the blow exerted by the type bar.

Another form of mechanism for regulating the period of contact is shown in Figs. 4 and 5. In this form the contact 32 is mounted on an insulating block 115 which is carried on an arm 116 having a rack 117 meshing with a worm 118. The worm 118 is provided with a knurled handle 119 which may be rotated to adjust the position of the contact 32 and thus regulate the force of the blow of the type bars in the manner already explained.

We claim:—

1. The combination with a typewriter having case shift mechanism, of a solenoid for actuating said case shift mechanism, a shift key for controlling said solenoid, means for automatically de-energizing said solenoid at the close of an operation thereof, a detent movable into position to retain said case shift mechanism in shifted position, a spring for moving said detent into operative relation with said case shift mechanism, and means connected with said shift key for holding said detent out of operative position when said shift key is released but permitting operation of said detent when said shift key is depressed.

2. The combination with a typewriter having case shift mechanism, of a solenoid for actuating said case shift mechanism, and a spring interposed between said solenoid and case shift mechanism arranged to permit excess movement of said solenoid when said case shift mechanism reaches the limit of its movement.

3. The combination with a typewriter having a shift frame, of a solenoid for actuating said shift frame, a spring interposed between said solenoid and shift frame to permit excess movement of said solenoid when said shift frame reaches the limit of its movement, and means for holding said spring under tension in the position to which it is moved by said solenoid.

4. The combination with a typewriter having a shift frame, of a solenoid, a spring interposed between said shift frame and solenoid to transmit movement from said solenoid to said shift frame and to permit

excess movement of said solenoid when said shift frame has reached the limit of its movement, a shift key, and a detent controlled by said shift key for maintaining said spring under tension independently of said solenoid.

5. The combination with a typewriter having a shift frame, of a solenoid having a plunger for actuating said shift frame, a spring interposed between said plunger and shift frame for transmitting movement from said plunger to said shift frame, said spring being arranged to permit excess movement of said plunger after said shift frame reaches the limit of its movement, a shift key for controlling said solenoid, and a detent actuated by said shift key for maintaining the tension in said spring after said solenoid has been de-energized.

6. The combination with a typewriter having a shift frame, of a solenoid having a plunger for actuating said shift frame, a spring interposed between said shift frame and plunger to transmit movement from said plunger to said shift frame, a shift key for controlling said solenoid, means for automatically de-energizing said solenoid at the close of an operation thereof, a detent for retaining said spring under tension after said solenoid has been de-energized, and means for releasing said detent when said shift key is released.

7. The combination with a typewriter, of a solenoid for actuating said typewriter, a contact member for controlling said solenoid, a spring for closing said contact member, means for holding said contact member open against the force of said spring, a key for releasing said holding means, and means for re-engaging said contact member with said holding means when said solenoid is energized.

8. The combination with a typewriter, of a solenoid for actuating said typewriter, a contact member having a fixed and a movable stop thereon, a spring for actuating said movable stop, a detent arranged to engage said fixed stop to hold said contact member open, means for shifting said detent out of engagement with said fixed stop to permit said contact member to close, and means for restoring said contact member to open position, said movable stop being operated by said spring to engage said detent when said contact member is restored to open position.

9. The combination with a typewriter, of a solenoid for actuating said typewriter, an electric circuit for energizing said solenoid, a contact member for controlling said electric circuit, said contact member having a fixed and a movable stop thereon, a spring for operating said movable stop, a detent for engaging said fixed stop to hold said contact member open, key controlled means

125

130

for shifting said detent to release said fixed stop, said detent operating to move said movable stop against the tension of said spring, and means for restoring said contact member to open position, said movable stop being freed to engage said detent and retain said contact member in open position when so restored, said detent being arranged to

shift from said movable stop to said fixed stop upon return movement of said key controlled means. 10

In testimony whereof we have signed our names to this specification on this second day of October A. D. 1925.

OTTO A. HOKANSON.
JAMES F. KOCA.
